DESIGN FOR A BOOKCASE

Gerald Johnson, George Cushing, and Thomas G. W. Nevell, New York, N. Y., assignors to The Globe-Wernicke Company, Cincinnati, Ohio, a corporation of Ohio

Application November 26, 1940, Serial No. 96,839

Term of patent 14 years

To all whom it may concern:

Be it known that we, Gerald Johnson, George Cushing, and Thomas G. W. Nevell, citizens of the United States and residents of New York, in the county of New York and State of New York, have invented a new, original, and ornamental Design for a Bookcase, of which the following is a specification, reference being had to the accompanying drawing, forming a part thereof.

In the drawing, the single figure is a perspective view of a bookcase showing our new design.

The rear of the device is substantially plain and the side not illustrated is substantially similar to that shown.

We claim:

The ornamental design for a bookcase, substantially as shown and described.

GERALD JOHNSON.

GEORGE CUSHING.

THOMAS G. W. NEVELL.
